JOINT

Torvald Thompson, New York, N. Y.

Application July 31, 1934, Serial No. 737,728

2 Claims. (Cl. 304—38)

This invention relates to an improvement in scaffolds and has reference particularly to the type of scaffold supports used on the outside construction work of modern buildings, which require apparatus of particularly heavy duty, convenience of installation, absolute security and ease of manipulation even under very heavy loads.

5 My invention has for its principal object to provide a scaffold which may be adjusted for heavy or light duty without requiring additional 10 hands to manipulate the mechanism.

A further object of this invention is the arrangement of a connecting device at the end of the scaffold platform, and a common means for readily 15 manipulating two scaffolds so that they may be connected together even by a single person.

Another object is to provide means whereby one 20 man with the aid of this invention and without any other outside aid may connect very heavy scaffolds together so that they will not separate under any conditions.

Other and further objects will present themselves upon reading the following description and will become obvious to those versed in the 25 building construction arts upon reading the following specification in conjunction with the annexed drawing.

The foregoing objects have been accomplished by a device consisting of the arrangement and 30 combination of parts illustratively exemplified in the accompanying drawing, in which:—

Figure 1 is a front elevation view of a scaffold shown suspended from supports fronting on a building wall.

35 Figure 2 is an end elevation and sectional view of the scaffold showing the method and means used to connect the winch or hoisting mechanism to the scaffold platform and is taken on the line 2—2 of Fig. 1.

40 Figure 3 is an enlarged plan view taken from above, of the apparatus shown in Fig. 2, showing the details of the invention more clearly.

Figure 4 is a side view of the apparatus shown in Fig. 3, taken on the line 4—4 thereof, with a 45 portion of the equipment broken away to show the details of the connecting mechanism in greater detail.

Figure 5 is another view taken along the line 5—5 of Fig. 4, and showing further details of 50 construction of the joint or joining mechanism.

Referring, now, more particularly to the drawing, the overhead beams or girders, temporarily installed in the steel structures of the buildings at an elevation above that to be covered by the 55 operations of the crew on the scaffold, are not

shown. However, the scaffold proper is suspended from these beams by means of the usual steel cable 11, which is looped at its upper end around these beams.

The platform frame forming the base of the scaffold, comprises in each instance, two pairs of slightly separated parallel channel beams 12, disposed longitudinally of the scaffold and with their flanges directed inwardly towards each other, as carefully illustrated in Figure 3. Adjacent each 10 end, the beams 12 are tied together in their spaced relation by a rod 13, anchored in the web portions of the beams. The rods 13 are separated from each other a sufficient distance to accommodate the closed end of a U-shaped hanger 14 there-over, as illustratively exemplified in Figure 2. The material of the hanger 14 is of a width equal to the space between the beams and the upright arms 14, 15 project to a substantial height above the beams 12 to support the mechanism of the 20 hoist. In assembly a number of these platform units are used, depending of course, upon the length of scaffolding to be set up, and when the number is determined they are separated from each other and planks 16 are placed over the pairs 25 of beams 12 and perpendicularly to the longitudinal axis of the scaffold. As illustrated in Figure 1 and Figure 2, the planks 16 are accommodated between the parallel channel beams 12 of the scaffolding and are held in place by short 30 sections 17 on their under sides.

A rack support 18, Fig. 1 is provided with bracket portion 19 and attached by means of bolts to one side of the hanger 14, 15. A safety bar or rod 9 is inserted across from one of these supports 18 to its neighboring support 18 on another hanger.

Thus far only the overhead supporting beams and the scaffold platform have been described. The present invention contemplates an improved 40 joint for linking the scaffolds or scaffold units together at their bases or platforms.

As stated in the foregoing description, each hanger 13, 14, 15 supports a hoist comprising a 45 drum 22 rotatably carried between the upright arms 14, 15 about midway of their height.

In order to connect two neighboring scaffolds together with their associated parts, by means of the invention or device, the U-shaped element 25 is dismantled by removing the bolt member 26 50 and placing the U-shaped member 25 around the bolt 27 of the left hand scaffold of Fig. 3 and Fig. 4. Then rod 13 which may or may not have been withdrawn, is put in place in the hole provided therefore in the frame member 14. Next, the 55

scaffold on the right of the above enumerated figures is moved over and bolt member 28 is inserted into the U-shaped member 25. The two scaffolds will then be found to have the channel members 12 thereof aligned as to the holes 29 thereof, and rod 13 may be inserted connecting frame member 14 together with the channel members 12. As a final step, bolt 26 is inserted in place and plate 30 is placed over the space between the two scaffold platforms.

Bolt member 31 by means of which U-shaped member 25 is firmly fastened to frame member 14 and angle-iron 33 may be made as shown in full lines, encircling rod 13. This bolt 31 serves as an additional support for the scaffold and in addition keeps the channel portions 12 properly spaced and in place.

To connect the ordinary scaffolds carrying a light load, either boards are placed across the two scaffolds to connect them or cords are used. This is a dangerous condition, as a break in one cable will cause the workers to be plunged to their death in the street below. Furthermore, one man

is not sufficient to perform this task. If several men stop their work to assist in the lifting operation or in the joining operation, then considerable time is lost and in the majority of cases there is not enough room to care for the men at the point of joining.

What is claimed is:

1. A flexible joint for a scaffold comprising a bar having a pair of arms forming a U, a pair of scaffold platforms, a loop on each platform, each of said arms being insertable into one of said loops at a time, and means bridging said arms and locking the loop members in place thereon.

2. A flexible joint for a scaffold comprising a bar having a pair of arms forming a U, a pair of scaffold platforms, a loop on each platform, each of said arms being insertable into one of said loops at a time, and means bridging said arms and locking the loops in place thereon, said U having a groove for connecting a scaffold hoist thereto.

TORVALD THOMPSON.
